UNITED STATES PATENT OFFICE

DORSEY M. WIRTH, OF BUCYRUS, OHIO

BELT BUCKLE

Application filed August 27, 1931. Serial No. 559,695.

This invention appertains to new and useful improvements in belt buckles and is a continuation in part of application Serial No. 549,224 and an improvement over Patent No. 5,1814,275.

The principal object of this invention is to provide an expandable belt buckle which allows a comfortable degree of resiliency between the buckle end of the belt and the portion of the opposite end of the belt attached to the buckle.

During the course of the following specification and claims, other important objects and advantages of the invention will become apparent to the reader.

In the drawings:—

Figure 1 represents an inside elevational view of one form of the belt buckle showing the removable hook type.

Fig. 2 represents a longitudinal sectional view taken substantially on line 2—2 of Fig. 1.

Fig. 3 represents an inside elevational view of a modification of the invention showing the hook attached type.

Fig. 4 represents a sectional view taken substantially on line 4—4 of Fig. 3.

Fig. 5 represents an inside elevational view of another modification of the invention showing the pivoted loop type.

Fig. 6 represents a sectional view taken substantially on line 6—6 of Fig. 5.

Fig. 7 represents a perspective view of the slide plate employed in Fig. 5.

Fig. 8 represents a perspective view of the modification of the plate shown in Fig. 7, also showing the pin which is used in place of the pintles in Fig. 7.

Fig. 9 represents an inside elevational view of another modification of the invention, showing only a single stem connection, and being of a type shown in Fig. 5.

Referring to the drawings wherein like numerals designate like parts, it can be seen that the form of the invention disclosed in Fig. 1, involves a plate 5 having an ovate-shaped opening 6 in the enlarged end portion 7 thereof. The reduced end portion of the plate 5 is provided with a laterally disposed flange 8 having a pair of openings there-

through for slidably receiving the side rail portions *a—a* of the frame denoted by numeral 9, these side rail portions *a—a* being parallel and connected together at one end of the frame by the arcuate portion *b* at its opposite end by the straight portion *c*, this latter portion *c* being adapted for disposition through the usual loop 10 on the buckle end of the strap 11.

A coiled compressible spring 12 is convoluted on the rail portions *a—a* and curved portion *b* and has its ends impinging against the inside of the flange 8 so as to normally maintain the straight portion *c* urged toward the outside of the flange 8.

Numeral 12 represents an ovate-shaped block having a tongue or hook 13 extending therefrom and obviously by inserting this hook 13 through the opening 6 through the pants side of the plate 5 and urging the same through an opening in the belt 11, the buckle of plate 5 will be secured to the free end portion, or apertured end portion of the belt, while the plate 5 is in turn connected resiliently to the buckle end of the belt by the aforementioned frame 9 and associated spring 12.

Fig. 3 is only modified in respect to the structure shown in Fig. 1 to the extent that the tongue 13a is swingably connected to the plate 5 as at 12a and is not a separate unit as in Fig. 1.

Fig. 5 discloses the loop plate type of buckle wherein the loop plate is denoted by numeral 14 the same being provided with the usual inturned portions 15—15 which in the present case are provided with collar formations 16.

Associated with this type of buckle is the plate 17 having a laterally disposed flange 18 at one end and a reduced portion 19 at its opposite end. As shown in Fig. 7, this reduced end portion 19 is provided with laterally disposed pintles 20—20 for engagement into the collars 16—16, whereby the plate 17 is swingably connected to the loop plate 14.

As is apparent in Fig. 5, the flange 18 is provided with a pair of openings for receiving the side rails *a—a* of the frame which is

constructed in the same manner and equipped with the same type of spring as shown in Fig. 1.

Fig. 8 discloses that instead of having the reduced end portion 19 provided with integral laterally disposed pintles 20—20, the reduced portion 19 is bent to form a barrel 21 through which a pin 22 is disposed and adapted to engage at its ends into the collars 16—16, thus also swingably connecting the plate 17 to the loop plate 14.

Fig. 9 discloses another modification of the invention, wherein, instead of providing the frame 9 as in the form shown in Fig. 5, a single T-shaped member 23 is employed, the transverse head portion 24 being engaged with the strap loop or anchor 10, while the leg portion of this T-shaped stem is disposed through a single opening in the flange 18a of the plate 17a, the plate 17a being otherwise constructed as shown in Fig. 7.

The free end of the leg portion of the T-shaped stem 23 is provided with a stop or enlarged formation 25 and between this and the flange 18a the compressible coiled spring 26 is interposed.

Obviously, the plate 5, plate 17 and plate 17a are all equivalents in the different forms and is a generic feature of the invention.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. In a belt buckle comprising a plate provided at one end with means for engaging the adjustable end of the belt, said plate being provided at its opposite end with a laterally disposed formation having an opening therein, a slidable member disposed through the opening and provided with a transversely extending straight portion at its outer end and a spring interposed between the inner end of the slidable member and the inner side of the laterally disposed formation the other end of the belt being secured to the straight portion.

2. A belt buckle of the character described comprising a plate provided at one end with a laterally disposed flange having a pair of openings therein, means at the opposite end of the plate for engaging the adjustable end portion of a belt, an open frame provided with a pair of parallel side portions slidably disposed through the openings, said frame being provided with an arcuate end portion and a straight transverse end portion, said straight transverse end portion being engageable with the free end of the belt and being enlarged, and a compressible coiled spring disposed on the frame along the side portions

and arcuate end portion and abutting against the inner side of the flange.

In testimony whereof I affix my signature.
